UNITED STATES PATENT OFFICE

HENRY W. PRATT, OF JERSEY CITY, NEW JERSEY, ASSIGNOR TO WILLIAM H. LUTTON COMPANY, A CORPORATION OF NEW JERSEY

HANGER FOR SLAT SHADES

Application filed August 22, 1931. Serial No. 558,710.

This invention relates in general to a hanger for supporting slat shades upon greenhouses, porches and the like. Slat shades are usually composed of a plurality of parallel 5 thin strips of material, such as wood or metal, hingedly connected at their longitudinal edges, the shade being supported at its upper edge and capable of being rolled and unrolled from and to its other edge.

10 Heretofore, in the mounting of slat shades upon greenhouses, it has been the practice to drive nails or like fasteners through the slats into the sash rails and glazing bars. This practice is objectionable in that it is almost impossible to remove the shades without splitting or otherwise damaging the slats. Furthermore, the frequent driving of nails or the like into the glazing bars often splits or otherwise damages them. Also, considerable 15 time and skill is required to properly apply and remove the shades. It will be understood that slat shades are generally used on greenhouses only during the summer.

One object of my invention is to provide 20 a novel and improved hanger by which slat shades and the like can be easily and quickly applied to and removed from a support, such as a greenhouse roof, in a short time, by relatively unskilled persons, and without 25 the aid of tools and separate fasteners such as nails or screws, so that the shades can be applied and removed without the possibility of damaging either the shade or the glazing bars.

30 Further objects are to provide such a fitting which permits application and removal of the shades by operations similar to simple buttoning and unbuttoning, whereby the operations can be easily and quickly performed with certainty of satisfactory results, even by a relatively unskilled person.

Other objects are to provide a slat shade hanger which shall comprise a base plate to be attached to a support, for example, a glazing bar, and having a plurality of upstanding lugs spaced apart a distance substantially equal to the width of a slat of a slat shade to receive a slat between them, said lugs having alined openings whose axis is transverse to a slat disposed between the lugs, and a member

to be removably inserted in said openings and overlie said slat; to provide such a hanger which may be easily and quickly secured in position and permanently remain, so that the slat shades may be applied to and removed therefrom by simple manipulation of said pin; to provide such a hanger which shall also serve to receive the fixed ends of pull ropes for rolling and unrolling a slat shade; and to obtain other advantages and 55 results which will be brought out by the following description.

Referring to the accompanying drawings in which corresponding and like parts are designated throughout the several views by 60 the same reference characters,

Figure 1 is a fragmentary perspective view of the upper portion of a greenhouse roof having slat shade hangers embodying my invention applied thereto.

Figure 2 is an enlarged fragmentary top plan view of a slat shade hanger constructed in accordance with the invention, showing a slat shade secured thereto.

Figure 3 is a transverse vertical sectional view on the line 3—3 of Figure 2.

Figure 4 is a horizontal sectional view on the line 4—4 of Figure 3, and

Figure 5 is a vertical longitudinal sectional view on the line 5—5 of Figure 2.

Specifically describing the illustrated embodiment of the invention, I have shown the hanger A as used for securing a slat shade B of known construction upon a greenhouse roof C, although it should be understood that the hanger may be used for supporting slat shades or other similar devices upon any desired support. The greenhouse roof C includes glazing bars D each of which has a wooden core E for supporting the glass panes F, and a portion of the core projects upwardly on the outside of the roof as indicated at G; and my hanger when used on greenhouse roofs may be conveniently attached to the projecting portions G of glazing bars.

The hanger A comprises a base plate 1 formed of suitable material, preferably rust-proof metal, and the underside of the base plate is preferably formed with a longitudinal groove 2 to neatly receive the projecting

portion G of the glazing bar. The base plate is also formed with openings 3 to receive suitable fasteners, such as screws 4, for positively securing the base plate to the glazing bar.

The upper side of the base plate has a pair of upstanding lugs 5 which are spaced apart a distance approximately equal to the width of one of the slats 6 of the slat shade B, and 10 preferably the lugs 5 have at the base portions thereof at each side, straight surfaces perpendicular to the upper side of the plate to neatly engage the sides 7 of the slats. At 15 a distance from the upper side of the base plate somewhat greater than the thickness of the slats 6, the lugs 5 are preferably provided with axially alined openings 8 to slidably receive a pin 9, the axis of said openings being transverse to the slats so that when said 20 pin is inserted into the openings, it will overlie the slats, as clearly shown in Figures 2, 4 and 5 of the drawings.

It will be understood that the hangers A are permanently applied at the proper positions upon the structure on which it is desired to hang a slat shade. In applying a slat shade to the hangers, the pins 9 are first removed, after which one of the slats is arranged between the lugs 5 of each hanger. 25 Preferably, a slat is also disposed at the outer side of each of the lugs 5 as shown in Figures 2 and 5. The slats 6 nicely fit the spaces between the lugs 5 and the lugs are preferably of a thickness substantially equal to the 30 distance between the slats, so that the slats at the outer sides of the lugs also neatly engage the lugs. Then the pins 9 are inserted 35 into the openings 8 so as to overlie the slats. When thus mounted the slats are held 40 against movement laterally in both directions by the pins 9 and the lugs 5, the weight of the shade being largely assumed directly by the lugs 5. To prevent endwise movement 45 of the slats 6, a screw-eye 10 may be secured in the slat between the lugs 5 in alinement with the openings 8, so that the pin 9 also passes through the screw-eye 10.

To remove the shade from the hangers it 50 is merely necessary to remove the pins 9 from the openings 8 and pull the slats outwardly from between the lugs 5. Obviously these operations can be easily and quickly performed by a relatively unskilled person, without separate tools or fasteners and without possibility of injury to either the slats or the support upon which the shade is mounted.

The base plate 1 may also have a perforated lug 11 at one or each of its longitudinal sides for attachment thereto of one end 12 of a cord 13 to be used for rolling and unrolling the shade. As usual, after attachment of the end 12 of the cord to the base plate, the cord is brought downwardly beneath the shade 55 around the lower end of the shade, upward-

ly to a pulley 14 mounted above the upper edge of the shade, and then downwardly to a convenient location for operation, for example at the side of the greenhouse.

While I have shown and described the 70 hanger as embodying certain details of construction, it should be understood that this is primarily for illustrating the principles of the invention and that many modifications and changes may be made in the details of 75 construction without departing from the spirit or scope of the invention.

Having thus described my invention, what I claim is:

1. A hanger for slat shades comprising a 80 base plate to be attached to a support, and means for separably connecting a slat shade to said base plate.

2. A hanger for slat shades comprising a 85 base plate to be attached to a support and having an upstanding lug to be disposed between two adjacent slats, and means cooperating with said lug to hold said slats against displacement from said base plate.

3. A hanger for slat shades comprising a 90 base plate to be attached to a support and having an upstanding lug to be disposed between two adjacent slats, said lug having an opening whose axis is transverse to such slats when the lug is disposed therebetween, and 95 a member to removably fit said opening and overlie the slats.

4. A hanger for slat shades comprising a 95 base plate to be attached to a support and having a plurality of spaced upstanding lugs 100 to receive a slat of a slat shade between them, and a member cooperating with said lugs to overlie such slat and separably connect it to said base plate.

5. A hanger for slat shades comprising a 105 base plate to be attached to a support and having a plurality of spaced upstanding lugs to receive a slat of a shade between them, said lugs having axially alined openings transverse to such slat when the same is disposed between said lugs, and a member 110 removably arranged in said openings to overlie said slat.

6. A hanger for slat shades comprising a 115 base plate to be attached to a support and having a plurality of upstanding lugs spaced apart longitudinally of said base plate a distance approximately equal to the width of a slat of a slat shade to receive a slat between them, said lugs having alined openings 120 spaced from the base plate a distance greater than the thickness of the slat with their axes transverse to such a slat, and a pin to be inserted through said openings and overlie a slat disposed between said lugs.

7. A hanger for slat shades comprising a 125 base plate to be attached to a support and having a plurality of upstanding lugs spaced apart longitudinally of said base plate a distance approximately equal to the width of a 130

slat of a slat shade to receive a slat between them, said lugs being of a thickness substantially equal to the distance between the slats of such shade to be disposed between adjacent slats and having aligned openings spaced from the base plate a distance greater than the thickness of the slat with their axes transverse to such slats, and a pin to be inserted through said openings and overlie a slat disposed between said lugs and slats at opposite sides thereof.
